Primary Examiner — Cynthia M Chin*(74) Attorney, Agent, or Firm* — SAIDMAN DesignLaw Group(57) **CLAIM**

The ornamental design for a tricycle, as shown and described.

DESCRIPTION

FIG. 1 is a front perspective view of a tricycle showing my new design;

FIG. 2 is a rear perspective view thereof;

FIG. 3 is a top view thereof;

FIG. 4 is a rear view thereof;

FIG. 5 is a front view thereof;

FIG. 6 is a right side view thereof; and,

FIG. 7 is a left side view thereof.

The broken lines illustrate portions of the tricycle and form no part of the claimed design.
